UNITED STATES PATENT OFFICE.

HOMA A. STAGGS, OF HENRIETTA, TEXAS.

DESIGN FOR A MATCH SCRATCHER.

Application filed April 23, 1921. Serial No. 463,961. Term of patent 7 years.

To all whom it may concern:

Be it known that I, HOMA A. STAGGS, a citizen of the United States, residing at Henrietta, in the county of Clay and State of Texas, have invented and produced a new, original, and ornamental Design for a Match Scratcher, of which the following is a specification, reference being had to the accompanying drawings, forming a part thereof.

In the aforesaid drawing the figure is a plan view of a match scratcher showing my new design as a label to be used on packages of cigarettes and tobacco.

I claim:

The ornamental design for a match scratcher, as shown.

In testimony whereof I have signed my name in the presence of two subscribing witnesses.

HOMA A. STAGGS.
